CLAIM

The ornamental design for a tape printing machine, as shown and described.

DESCRIPTION

FIG. 1 is a perspective view of a tape printing machine;

FIG. 2 is a top view thereof;

FIG. 3 is a front view thereof;

FIG. 4 is a right-side view thereof;

FIG. 5 is a left-side view thereof;

FIG. 6 is a rear view thereof;

FIG. 7 is a bottom view thereof; and,

FIG. 8 is a cross-sectional view thereof taken along the line 8—8 of FIG. 2.

The broken lines depict environmental subject matter only and form no part of the claimed design.

UNITED STATES PATENT AND TRADEMARK OFFICE
CERTIFICATE OF CORRECTION

PATENT NO. : Des. 601,182 S
APPLICATION NO. : 29/334040
DATED : September 29, 2009
INVENTOR(S) : Masayoshi Mita et al.

Page 1 of 1

It is certified that error appears in the above-identified patent and that said Letters Patent is hereby corrected as shown below:

Title page, delete the following:

Item "(75) Inventors: Masayoshi Mita, Nagoya (JP);
Mitsuhara Hattori, Nagoya (JP)"

And replace with:

--(75) Inventors: Masayoshi Mita, Nagoya (JP);
Mitsuharu Hattori, Nagoya (JP)--

Signed and Sealed this

Seventeenth Day of November, 2009

David J. Kappos
Director of the United States Patent and Trademark Office
